UNITED STATES PATENT OFFICE

153,438

DESIGN FOR A JACKET

Oscar E. Kratz, Kansas City, Mo., assignor to The
H. D. Lee Company, Incorporated, Kansas City,
Mo., a corporation of Kansas

Application July 24, 1948, Serial No. 147,749

Term of patent 14 years

(Cl. D3—4)

To all whom it may concern:

Be it known that I, Oscar E. Kratz, a citizen of the United States, residing at Kansas City, in the county of Jackson and State of Missouri, have invented a new, original, and ornamental Design for a Jacket, of which the following is a specification, reference being had to the accompanying drawing, forming part thereof.

Fig. 1 of the drawing is a front view of a jacket showing my new design, and

Fig. 2 of the drawing is a rear view of the jacket.

In the drawings the dotted lines indicate stitching made with thread of a color contrasting to the color of the material from which the body of the jacket is made.

I claim:

The ornamental design for a jacket, as shown and described.

OSCAR E. KRATZ.
